UNITED STATES PATENT OFFICE.

LULAH M. SMIDT, OF LOS ANGELES, CALIFORNIA.

HAIR CURLER.

Application filed July 6, 1921. Serial No. 482,870.

To all whom it may concern:

Be it known that I, LULAH M. SMIDT, a citizen of the United States, and resident of the city of Los Angeles, in the County of Los Angeles and State of California, have invented new and useful Improvements in Hair Curlers, of which the following is a full, clear, and accurate disclosure.

This invention has to do with a device useful for curling or waving hair, or the like, and it is an object of the invention to provide a simple, effective, improved device of this general character.

A noteworthy feature of the invention is the provision of a device on which hair can be easily and quickly arranged in a manner to produce a graceful effective wave or curl. The device is such that hair can be arranged on it in different manners to obtain different waving or curling.

Another feature of the device is its adjustability. The invention provides adjustability in the device so that it can be used to handle hair in various manners and to handle various qualities of hair.

The various objects and features of the invention will be best and more fully understood from the following detailed description of typical preferred forms of the invention throughout which reference is had to the accompanying drawings, in which:

Fig. 1 is a view illustrating the manner in which a person can handle or manipulate the device provided by the present invention to arrange hair on it; Figs. 2, 3 and 4 are enlarged views illustrating several successive steps during the arrangement of hair on the device in a typical manner; Fig. 5 is an enlarged elevation of the device; Fig. 6 is an enlarged detail transverse sectional view of the device, being a view taken as indicated by line 6—6 on Fig. 5; Fig. 7 is a view similar to Fig. 5 of another form in which the invention may be embodied, and Fig. 8 is a perspective view of an embodiment of the invention similar to that shown in Figs. 1 to 6, showing another form of construction.

The device illustrated in Figs. 1, 2, 3, 4, 5, and 6 of the drawings, comprises a main part or body 10, an end or outer cross arm 11 and an inner cross arm 12. In the case of the particular device illustrated in the drawings the body 10 is somewhat longer than either of the arms and the arms are equal in length. The arms 11 and 12 are preferably, though not necessarily, arranged

to be truly transverse of the body 10 and are preferably arranged so that they extend equal amounts on either side of the body 10. The arm 11 is arranged permanently at the end of the body 10 being preferably integral with the body 10. The inner arm 12 is, according to the present invention, detachable from the body 10 and adjustable longitudinally of the body 10. In the particular form of the invention now under consideration the center portion 13 of the inner arm 12 is somewhat enlarged and has an opening 14 formed through it to slidably receive the body 10. It is preferred, although not necessary, that the various parts of the device, that is, the body 10 and the arms 11 and 12, be round in cross sectional configuration as such shape is most desirable for the average work. When the body 10 is round in cross sectional configuration the opening 14 provided in the middle portion 13 of the inner arm 12 is made round to accurately slidably receive it. The body 10 preferably fits tightly enough in the opening 14 to prevent the inner arm 12 being moved by ordinary handling of the device, yet loosely enough to allow it to be moved by hand when it is desired to adjust it to various positions.

In operation the inner arm 12 is arranged at the most advantageous point along the body 10 and in some cases several inner arms are arranged on the body 10. When the inner arm or arms, as the case may be, have been arranged or properly adjusted on the body 10, hair H can be wrapped or arranged around and between the body and arms in various manners. In Figs. 2, 3, and 4 of the drawings I illustrate a manner in which hair H can be wrapped on the device to produce a wave in it known as a marcel wave. This is obviously only one of several manners in which hair may be wrapped on the device and is intended only to illustrate a typical practical application of the device. Fig. 2 illustrates the manner in which the wrapping is started, Fig. 3 illustrates the wrapping partially completed, and Fig. 4 illustrates the wrapping completed. It will be understood, of course, that the wrapping can be continued until all of the hair or the desired portion of the hair, is on the device.

In Fig. 7 of the drawings I show a form of the invention wherein there is a body 10^a and a cross arm 12^a. In this case the body and arm are the same length, are integral with each other, and are arranged

transversely of each other, to form a cross with arms of equal length. It will be obvious how hair can be arranged or wrapped on this form of the invention in various ways and that this form of the invention is particularly useful in handling comparatively short hair.

In Fig. 8 of the drawings is illustrated a form of the invention similar to that illustrated in Figs. 1, 2, 3, 4, 5, and 6. The form of the invention shown in Fig. 8, however, differs from that shown in the other figures in that the inner arm 12^b is not slidably adjustable on the body 10^b but is adapted to be adjusted longitudinally relative to the body 10^b by being arranged through different openings 20 formed transversely through the body 10^b to slidably receive it. There is a series of openings 20 formed in the body 10^b so that the arm 12^b can be arranged at various points along it. The outer arm 11 is preferably integral and solid with the body 10^b like the arm 11 in the form of the invention first described. In the form of the invention shown in Fig. 8, like in the other forms herein set forth, the various parts are preferably round in cross sectional configuration, and the arm 12^b preferably fits the openings 20 so that it can be moved by hand but will not become displaced by ordinary handling or manipulation of the device.

As far as the present invention is concerned it is more or less immaterial what material is used in the formation of the device. However, when the device is not to be heated it is preferred that it be formed of rubber, or the like, and when it is to be heated that it be formed of a comparatively light metal or alloy of metals which will not melt at temperatures to which the device is apt to be heated.

Having described only typical embodiments of my invention, I do not wish to limit myself to the particular features hereinabove set forth but wish to reserve to myself any changes or variations that may appear to those skilled in the art and that may fall within the scope of the following claims.

Having described a preferred form of my invention, I claim:

1. A device of the character described comprising, a body, a cross arm in connection with the body, the arm being detachable from the body and adjustable longitudinally of the body.

2. A device of the character described comprising, a body, an arm at one end of the body, extending from two sides of the body at the same point longitudinally on the body and an arm intermediate the ends of the body extending from two sides of the body at the same point longitudinally on the body.

3. A device of the character described comprising, a body, an outer arm at one end of the body, and an inner arm intermediate the ends of the body and adjustable longitudinally of the body.

4. A device of the character described comprising, a body, an outer cross arm fixed at one end of the body, and an inner cross arm intermediate the ends of the body and arranged in connection with the body to be adjustable longitudinally of it.

5. A device of the character described comprising, two parts, one a body the other an arm, one of said parts having an opening slidably receiving the other part so that the arm is intermediate the ends of the body and extends from two sides of the body.

6. A device of the character described having a body, and a cross arm in connection with the body intermediate the ends of the body and extending from opposite sides of the body at the same point longitudinally of the body.

In witness that I claim the foregoing I have hereunto subscribed my name this 23 day of June, 1921.

LULAH M. SMIDT.
